UNITED STATES PATENT OFFICE.

GEORGE C. WILCKE, OF FINDLAY, OHIO.

STEP-LADDER.

1,269,142.

Specification of Letters Patent. Patented June 11, 1918.

Application filed May 10, 1916. Serial No. 96,668.

To all whom it may concern:

Be it known that I, GEORGE C. WILCKE, a citizen of the United States, residing at Findlay, in the county of Hancock and State 5 of Ohio, have invented certain new and useful Improvements in Step-Ladders, of which the following is a specification.

This invention relates to an improved extensible step ladder and the principal object of the invention is to provide an improved extensible step ladder having an improved means for slidably connecting the upper and lower sections of the step ladder and to further provide improved means for 10 15 slidably connecting the upper and lower sections of the rear support for the step ladder.

Another object of the invention is to provide improved means for releasably holding these extensible sections in an adjusted position and preventing the ladder from collapsing when in use.

Another object of the invention is to provide improved bracing means for the rear support, the bracing means being adjustable and permitted of being releasably held 20 25 in the adjusted position.

Another object of the invention is to so construct the means for slidably connecting the sections of the ladder and support and 30 35 releasably holding the sections in the adjusted position that these parts will be securely and firmly held in an extended position but at the same time to provide fastening means so constructed that the parts may be easily released and the ladder permitted to collapse when desired.

This invention is illustrated in the accompanying drawings, wherein:-

Figure 1 is a view showing the improved 40 45 step ladder in side elevation.

Fig. 2 is a view showing the improved step ladder in rear elevation.

Fig. 3 is a sectional view through the upper and lower sections of the step ladder 45 taken along the line 3-3 of Fig. 1.

Fig. 4 is a fragmentary view partially in elevation and partially in section showing the manner of releasably holding the sections of the rear support in an adjusted position.

Fig. 5 is a sectional view through one side portion of the rear support taken along the line 5-5 of Fig. 1.

Fig. 6 is a fragmentary perspective view 55 of the brace positioned between the step ladder and rear support.

The step ladder is provided with an upper section 10 and a lower section 11. The side bars of the lower section extend in diverging directions whereas the side bars of the upper section extend parallel so that the side bars of the upper section may be slidably positioned in the yokes 12 carried by the side bars of the lower section.

The rear support is also provided with an upper section 13 and a lower section 14, the lower section having its side bars extending in diverging relation and the upper section having its side bars extending parallel and extending through the eyes 15 which are secured to the side bars of the lower section and to the cross bar or bracing bar 16 connecting the upper end portions of the side bars of the lower section. Guiding strips or webs 17 are secured to the upper end 70 75 portions of the side bars of the lower section 14 and by engaging the outer side faces of the side bars of the upper section 13, brace the upper section and prevent this upper section from having transverse movement. Therefore the upper section and the lower section will be held firmly against transverse play and there will be no danger of the ladder toppling over when in use.

In order to releasably hold the upper sections of the step ladder and rear support in an adjusted position, there has been provided the pawls or latches 18 and 19 which are similar in construction and operation and are connected with the hinge brackets 85 90 20 and 21 secured to the side bars of the lower sections 11 and 14. These hinge brackets can be formed of sheet metal and as shown in Fig. 4 are secured by means of the screws 22 and have their side portions bent 95 to provide hinge ears 23 between which the pawls or latches will be mounted by means of the pivot pins 24. The side bars of the upper sections 10 and 13 will be provided with sockets 25 covered by the perforated 100 plates 26. After the upper sections of the step ladder and rear support have been raised to the proper position, the latches 18 and 19 will be swung to extend into the sockets 25 and the ladder will then be securely but releasably held at the proper 105 height.

The side bars of the rear support are hingedly connected with the upper portion of the step ladder by means of the strap 110 hinges 27 and in order to brace the rear support, there has been provided a brace in-

cluding the two sections or arms 28 and 29. These arms 28 and 29 are pivotally connected with the side bars of the lower sections of the step ladder and rear support and can be 5 adjusted longitudinally as the rear support is swung toward or away from the step ladder. The arm 29 is slotted as shown at 30 to receive the guiding pin 31 carried by the arm 28 and the arm 29 is provided at its 10 free end with a hook 32 which will fit into a selected socket 33 of the arm 28 thus securely but releasably holding the brace at the adjusted length. Therefore as the height 15 of the ladder is increased, the rear support can be moved farther away from the lower end of the step ladder thus providing the proper angle to support the step ladder and prevent it tilting over. When not in use, this step ladder can be collapsed and 20 then folded in the ordinary manner.

What is claimed is:—
A step ladder comprising upper and lower

sections slidably connected and each provided with side bars, the side bars of the upper section of the step ladder being provided with sockets, bearing brackets carried by the side bars of the lower section adjacent the upper end thereof, and pawls pivotally connected with the bearing brackets and extending across and resting flat upon the upper ends of the lower side bars and fitting into the sockets of the side bars of the upper section to releasably hold the upper section at an adjusted height, said pawls having their free ends cut to provide 30 cam faces causing the pawls to move to an inoperative position when the upper section is raised.

In testimony whereof I affix my signature in presence of two witnesses.

GEORGE C. WILCKE.
